(57) **CLAIM**

The ornamental design for a LED light device, as shown and described.

DESCRIPTION

FIG. 1 is a perspective view of an LED light device showing my new design;

FIG. 2 is a top plan view thereof;

FIG. 3 is a bottom plan view thereof;

FIG. 4 is a left side elevational view thereof;

FIG. 5 is a right side elevational thereof;

FIG. 6 is a front elevational view thereof; and,

FIG. 7 is a rear elevational view thereof.

The broken line disclosure represents a portion of the device which forms no part of the claimed design.
